SAILBOAT

Carter Pyle, 2920 Alexander Road, Laguna Beach, Calif.
92651, and Joseph M. Quigg, 7204 W. Ocean Front,
Newport Beach, Calif. 92660

Filed May 16, 1966, Ser. No. 2,303

Term of patent 14 years

(Cl. D71—1)

FIG. 5

FIG. 6

FIG. 7

FIG. 1 is a perspective view of a sailboat showing our new design;

FIG. 2 is a front elevational view thereof in enlarged scale and with the mast broken away in the interest of clarity;

FIG. 3 is a rear elevational view of said sailboat with the mast broken away in the interest of clarity;

FIG. 4 is a vertical sectional view taken along line 4—4 of FIG. 6 and with the mast broken away in the interest of clarity;

FIG. 5 is a side elevational view of said sailboat with the mast broken away in the interest of clarity;

FIG. 6 is a top plan view of said sailboat with the mast broken away in the interest of clarity; and

FIG. 7 is a bottom view of said sailboat.

We claim:

The ornamental design for a sailboat, substantially as shown and described.
